INTERNAL INSULATED STRUCTURAL
UNITCharles R. Weiller, Louisville, Ky., assignor to
Reynolds Metals Co., Richmond, Va., a corpora-
tion of Delaware

Application June 20, 1944, Serial No. 541,142

2 Claims. (Cl. 189—40)

The object of this invention is to provide an internally insulated structural beam, upright or other structural unit incorporating a plurality of metallic sheets with a core preferably of cellulosic material such as wood or wood composition, the metallic elements being spaced by the wood or wood composition and of such form and relation to each other that, when stresses are imposed upon the structural element, the metallic elements will coact one with the other and with the core, to adequately resist compression and tension strains.

In my preferred form, the metallic elements consist of aluminum alloy sheets, the alloys being selected to provide greatly augmented resistance to stress as compared with metallic forms of commercially pure aluminum. It will be understood, however, that the sheets may be made of metals and metal alloys other than aluminum. By aluminum alloys, I mean in the present instance, alloys which are predominantly aluminum, but which incorporate other metals to provide increase in yield and other strengths.

My invention is particularly applicable to buildings constructed largely of metal inasmuch as the conduction of heat from inner or outer wall which would occur with all metal beams and risers, is prevented.

One of the problems overcome by my invention is the effect of expansion and contraction upon a composite structural form, embodying a plurality of metallic sheets, preferably of aluminum alloys, and a core such as wood, to wit: that in the wide range of temperatures to which such a structural element is subjected there is high expansion and contraction of the metal and very much less expansion and contraction of the cellulosic core. For this reason in expansion of the metallic elements, there is a strong tendency toward separation of the metallic elements from the cellulosic core, to such an extent that up to the present time, so far as I am aware, such structural elements have not been considered commercially practical.

As an example, the coefficient of expansion of aluminum and many aluminum alloys in sheet form is .00001234. This means that a strip of aluminum 100 in. long will have an elongation between the lower temperature of -20° F. and 100° F. of .148 in. When it is considered, however, that ordinarily the aluminum alloy sheets in the core in commercial assembly and cohesion will be subjected to very much greater temperatures at the upper range, and then be brought down to room temperature, this factor causing

great expansion and contraction of the metal, the problem will be realized.

In view of the above, it will be seen that in one phase of my invention, means are employed for overcoming the effect of expansion and contraction of the metallic elements relatively to the cellulosic core.

In a second and primary phase of my invention, the metallic elements are so related to each other and to the core, that upon the imposition of stresses, as by normal loads, relatively thin aluminum alloy sheets will coact with very high efficiency to resist such loads. For this reason, very light constructions may be employed for the normal uses in building construction, as for example, floor beams, truss arrangements, division uprights, lateral wall risers, etc., etc.

In describing the invention with reference to the drawing, certain simple structural forms have been illustrated, these forms comprising four types of structural members adapted for use as vertical and horizontal supports and for general structural use.

In the drawing—

25 Fig. 1 is a perspective fragmentary view showing an I-beam adapted for use as a floor or ceiling beam and embodying the invention.

30 Fig. 2 is a view similar to Fig. 1 showing one top plate removed and part of the vertical rib, broken away, to illustrate formation of one type of core adapted for use herein.

35 Fig. 3 is a transverse section through a channel beam embodying the invention.

Fig. 4 is a transverse section through a T-beam embodying the invention.

Fig. 5 is a transverse section through an angle member adapted for corner wall support.

40 Fig. 6 is a schematic plan view showing wood core sections abutted and illustrating the lay of the grain in a preferred form of core arrangement when natural wood is employed.

45 Referring to Fig. 1 of the drawing, I have illustrated at 1 an I-beam which may consist of wood core elements and aluminum alloy sheets.

On each side of the I-beam an aluminum alloy channel member 1 is employed. Each channel member is separated by a core 2, which in the present example may be of natural wood. At top and bottom of the members 1 and 2 are transverse core pieces 3 which are covered on the outside by the metallic strips 4 which may be of the same strain-resisting aluminum alloy as the strips 1.

50 Reference to Fig. 2 will show that employing my invention with a natural wood core, single-

ply pieces may be used, the grain being shown as extending transversely of the central web and the upper and lower flanges of the structure.

In assembling the structure suitable adhesive may be applied to the inner face area between the core 2 and the channel members 1 and these elements brought together under pressure, and usually under heat. For example, I can employ a thermosetting adhesive, this being possible because of the ability of the core members to follow the metallic members in their expansion and contraction. Thus, the channel members may be subjected to high pressure, in a suitable press, to bring their faces into firm contact with the adhesive, and under heat and pressure the adhesive will become set and bond the metal and wood strongly together. Like action is had when the core members 3 are applied to the flanges. The strips 4 may be applied and bonded to the core members 3 prior to assembly with the channel members 1, but in usual practice the bonding pressure and heat (where heat is employed) will simultaneously be applied to the strips 4, and the surfaces of the channel members.

It has been stated herein that, in the form of the invention being described, the grain of the wood extends transversely of the metallic strips. Referring to Fig. 2, it will be seen that the core member 2 and also the core members 3 are composed of abutting wood veneer pieces. Thus, the lines of abutment run with the grain of the wood. The major expansion is longitudinally of the I-beam. As the metal expands, the wood may be considered as having an accordion action, because the wood structure is so arranged as to permit the metal to have such expanding and contracting effect upon the wood. Repeated tests of the structure under wide ranges of expansion and contraction have demonstrated that even with the use of a normal thermosetting adhesive having a very low degree of elasticity, the bond between the metal and wood is maintained without rupture. The structure is not only adapted for expansion and contraction under normal conditions of use, but will withstand such high degrees of temperature as required for the setting and bonding of the adhesive material, and required for transportation under severe conditions of heat and cold, particularly where aluminum is employed.

In the stress-resistance action of an I-beam constructed in accordance with the invention, and assuming that the beam is laid horizontally and that the major stress is imposed vertically thereon, the stresses are distributed according to the known distribution of stresses in a unitary steel I-beam. In my combination, there is this mutual coaction: The web 2 of wood prevents inner curvature or collapse of the metallic webs. The wood web and cohesion between the wood and the metallic webs prevents outer curvature and collapse of the metal. When the beam is subjected to heavy loads, the collapsing stress upon the metal is perpendicular to the flanges. The tensional resistance of the metallic members is substantial.

Referring to Fig. 3, it will be seen that the U-beam therein illustrated is composed of an outer metallic U-section 5, an inner metallic U-section 6, and three cellulose core strips 7.

The T-beam illustrated in Fig. 4 is composed of two abutting core members, as of wood, indicated at 8, two angle metallic sheet members 9, and an outer metallic strip 10.

The L-beam illustrated in Fig. 5 is composed of an outer angle member, of formed metallic strip, 11, and a like but smaller angle member 12, with a core composed of abutting core members 13, 14, as of wood.

Referring to Fig. 6, I have shown part of one of the core members, 2 or 3, as composed of butt joined wood veneer pieces, with the grain of each piece extending transversely of the core so that the grain will lie transversely of the beam or other structural member as a whole. In the expansion or contraction of the metallic covering composing the exterior of the structural form, this arrangement will permit expansion and contraction of the wood in directions transversely of the grain, with the so-called accordion effect hereinbefore mentioned.

It will be understood that the width of the butt joined wood sections may be as desired, the construction permitting all required lengths in the beam or other structure form. Thicknesses and depths of the web and flanges forming the core structure illustrated in Figs. 1 and 2, may be varied in accordance with the particular loads and stresses to which the structure will be subjected in use, and these factors also will control the gauge of the aluminum alloy or other metal employed for the exterior surfaces. These factors, also, will control the elements of the structure shown in Figs. 3 to 5 inclusive. It will be further understood that the exposed edges of the wood or other cellulosic core members may be so treated as to render them impervious to moisture, fire-resisting and termite-proof.

Among the advantages of my structural form are light-weight in ratio to stress resistance, internal heat insulation, sound deadening by reason of the cellulosic core, fire-resistance, and adequate resistance against the action of termites and ingress of moisture, since the small exposed edge area may readily be sealed, as by aluminum paint.

It will be understood that the structural units illustrated in the drawing, may widely be varied in form and proportions, being illustrated by the invention, what I claim and desire to secure by Letters Patent, being as follows:

1. An internally insulated structural member comprising a cellulosic core, composed of a plurality of angularly related elongated wood units, each wood unit consisting of butt joined wood pieces with the grain thereof extended transversely of the structural member, and a plurality of metallic strips surfacing the core and bonded thereto, said strips being formed of strain-resisting metal.

2. An I-beam structural member composed of an internal web-core of wood, opposed channel strips of metallic sheet bonded to the web-core, opposed flange core members of wood abutting the web-core and the flanges of the channel members, and surfacing strips of metallic sheet material bonded to the exterior faces of the flange core members.

CHARLES R. WEILLER.
